CLAIM

The ornamental design for a stud-mounted polycrystalline diamond cutting blank, as shown and described.

DESCRIPTION

FIG. 1 is a front elevational view of a stud-mounted polycrystalline diamond cutting blank showing my new design;

FIG. 2 is a left side elevational view, the right side elevational view being identical thereto;

FIG. 3 is a rear elevational view;

FIG. 4 is a top plan view; and,

FIG. 5 is a bottom plan view thereof.

FIG. 1

FIG. 2

FIG. 3

FIG. 4

FIG. 5
